UNITED STATES PATENT OFFICE.

FRANK L. ADAMS, OF RADNOR, OHIO, ASSIGNOR, BY MESNE ASSIGNMENTS, TO HIMSELF, AND CHARLES E. KAGAY, OF RICHWOOD, OHIO.

SILO.

1,232,161.

Specification of Letters Patent.

Patented July 3, 1917.

Application filed July 21, 1916. Serial No. 110,615.

To all whom it may concern:

Be it known that I, FRANK L. ADAMS, a citizen of the United States, residing at Radnor, in the county of Delaware and State 5 of Ohio, have invented new and useful Improvements in Silos, of which the following is a specification.

The invention relates to an improvement in silos, and particularly to a construction 10 whereby a silo, constructed of wooden blocks, may be made and maintained air-tight during the life of the silo.

The improvement consists in interfitting the meeting edges of the blocks and in forming 15 a channel in the horizontal meeting edges of the certain layers to receive a binding wire which is terminally provided with means whereby it may be adjusted and held in such adjusted relation.

20 The invention in the preferred form of details will be described in the following specification, reference being had particularly to the accompanying drawings, in which:—

25 Figure 1 is a broken sectional view showing a portion of the blocks arranged in silo forming relation;

Fig. 2 is a plan of the same;

Fig. 3 is a section on line 3—3 of Fig. 1;

30 Fig. 4 is a broken section showing the connection of the terminals of the clamping bands.

In constructing the improved silo, I utilize 35 blocks 1 of any appropriate length and width, and of suitable configuration so that when arranged in a series of horizontal rows, they will form a rounded silo of the desired diameter. The blocks are to be disposed so that the joints of one layer break with the 40 joints of the adjacent layers, and the meeting edges of the blocks of any one layer are formed with coöperating projections 2, in channels 3 to secure an interlocking relation.

Throughout the door opening of the silo, 45 which extends preferably throughout the length of the silo, the free edges of the

blocks, that is, the edge boundary of the door way, is provided with angle beams 4, arranged as shown in Fig. 4 to provide a bearing abutment against the ends of the 50 blocks.

Throughout certain layers of blocks, the number and relation to be determined by the dimension or size of the silo, the horizontal meeting edges of adjacent layers are 55 formed with channels 5, which together constitute an endless conduit when the respective layers are in silo forming relation. This conduit is designed to receive a binding or clamping wire 6, which extends throughout 60 the length of the silo, and its ends projected through the respective angle irons 4 of the door way. The free terminals of the binding wire are threaded and connected with the usual turn-buckle 7, for tightening the wire 65 to the desired extent, the threaded terminals being alone provided with jam nuts 8, which are threaded upon the wires to bear upon the angle irons. The wires are thus held in fixed binding relation, and the whole structure is 70 effectively clamped.

It is of course to be understood that aside from the details herein described, the silo is to be constructed in any preferred manner, the number of the binding wires being 75 optional as is also their diameter.

Having now described my invention, what I desire to secure by Letters Patent is:—

A silo made up of a series of interfitting 80 blocks arranged in horizontal rows, said silo being formed with a door opening, angle irons secured to and overlying the edges of said opening, binding wires completely housed in the blocks between the horizontal meeting edges of adjacent rows, turn- 85 buckles connecting the said terminals of the wires disposed in the door way, and jam nuts engaging the respective terminals of the wires and bearing against the angle irons. 90

In testimony whereof I affix my signature.
FRANK L. ADAMS.
